DOOR LOCK

Wilson S. Sidelinker, Wilmington, Mass.

Application September 9, 1942, Serial No. 457,694

4 Claims. (Cl. 70—299)

My invention relates to combination locks and it has for its object to improve the construction and operation of locks of the class referred to.

To these ends I have provided an improved combination door lock having an operating spindle provided at its opposite ends with knobs or handles and by means of at least one of said handles, viz., the outside knob or handle, the spindle is rocked back and forth to first adjust a set of tumblers to free the bolt or latch of the lock, and thereafter to retract said bolt or latch to unlock the door.

In the best form of my invention I have also provided means accessible from the inner side of the door which is manually operable to retract the latch or bolt independently of the spindle and tumblers. Also, means is provided for restoring the tumblers to their normal bolt-locking positions when desired, said means being preferably operated by rocking movement of the spindle.

Other features of the invention are hereinafter pointed out.

In the accompanying drawings:

Figure 1 is a side elevation, partly in section, of a mortise door lock constructed in accordance with this invention, a portion of the casing being removed to expose the interior thereof.

Figure 2 is a partial section on line 2—2 of Fig. 1.

Figure 3 shows the lock in section on line 3—3 of Fig. 1 and includes the adjacent portion of the door in which the lock is mounted.

Figure 4 is an elevation of the rocker member hereinafter described.

Figure 5 is a detail hereinafter described.

Figure 6 is a perspective view of the friction clutch bushing hereinafter described.

Figure 7 shows the positions of some of the parts of the lock mechanism preparatory to adjustment of the master slide or element which controls the tumbler adjusting pawls hereinafter referred to.

Figure 8 is a view similar to Fig. 7 but showing the positions of the parts after adjustment of the master slide or element.

Figure 9 is a plan view of the master slide or element.

Figures 10, 11 and 12 are, respectively, elevations of the tumbler slides 7, 5 and 3, hereinafter referred to.

Figure 13 is a detail of the bolt-pushing element hereinafter referred to.

The illustrated embodiment of my invention comprises a box-like casing that is indicated generally at 10 (Fig. 1), said casing comprising a

front wall 11, a back wall 12, oppositely disposed side walls 13 and 14 (Fig. 2), a top wall 15 and a bottom wall 16. The front wall 11 is provided with end extensions which are formed with screw holes for the reception of screws by means of which the lock is fastened to the door as shown in Fig. 3, with the casing occupying a mortise formed in the door D. The side wall 13 (Figs. 2 and 3) is made as a removable plate held in place by four screws whereof one is shown in Fig. 5.

Within the casing 10 there is provided a rocker member 17 (Figs. 1 and 4) that is spool-shaped and provided at its opposite ends with trunnions 18 which are rotatably mounted within apertures provided in the oppositely disposed side walls 13 and 14 of the casing. Within member 17 is provided a friction clutch bushing 19 (Figs. 6 and 7) which is split longitudinally as at 20 and whose interior is formed non-circular or square to receive within it a square spindle 21 whose opposite end portions extend through apertures formed through the opposite side walls of the mortise cavity and are provided, with handles or knobs 22 and 23, the former being disposed upon the outside of the door (Fig. 3) and the latter upon the inside thereof.

At its one end the rocker 17 is made with a radial flange 24 which is circular except for a peripheral notch or recess which provides a pair of opposed abutment shoulders 25 and 26 (Fig. 7), one at each end of said notch. At its opposite end the rocker 17 is made with a radial flange 27 (Figs. 3 and 4) that is formed with an outwardly extending arm 28 that is indicated by broken lines in Figs. 1, 7 and 8 but shown by full lines in Figs. 3 and 4. Between the flanges 24 and 27 (Figs. 1 and 3) are three pawls 3a, 5a and 7a which are pivotally mounted loosely upon a short shaft 29 that is mounted at its opposite ends in the flanges 24 and 27. These pawls co-operate with the master slide or element 38 (Figs. 1 and 9) and the tumblers 7, 5 and 3 (Figs. 3, 10, 11 and 12) as presently to be described.

Between the flanges 24 and 27 of the rocker 17 there is also provided an abutment bar 30 whose opposite ends are connected with said flanges. This abutment bar co-operates with a hook 31 whose shank is pivotally connected with a lever 32 that is pivotally mounted at 33 upon the side wall 14 of the casing. The lower end of this lever co-operates with the master slide and tumblers to re-set the same as presently to be described. Normally a spring 34 holds lever 32 at the limit of its movement in one direction against a stop 35.

A leaf spring 36 is fastened at its one end to the side wall 14 of the casing with its free end bearing yieldingly against the periphery of flange 24 and in position to co-operate with the opposed shoulders 25 and 26 thereby to serve as a feeler guide to the person operating the spindle to free and retract the bolt 37 of the lock by means of the handle or knob 22 upon the outside of the door D. The spindle 21 may be operated by means of either knob 22 or 23 to free and retract the bolt 37 but I preferably provide a finger piece 39 upon the inside of the door D by means of which the bolt 37 may be retracted independently of the rest of the lock mechanism. As shown in Fig. 2 this finger piece 39 is a short bar provided at one end with a reduced portion which is threaded and screwed tightly into a threaded hole 40 provided adjacent to the inner end of the bolt 37 from which it extends through a slot 41 formed in side plate 13 to the exterior of the door upon the inside of the latter, the adjacent side wall of the mortise being also slotted as indicated by dotted lines at 42 in Fig. 3, and the two slots 41 and 42 being in register and parallel with the longitudinal axis of bolt 37.

The bolt 37 is normally held in its projected door-locking position by a spring 44 whereof one end abuts the head of said bolt and the opposite end abuts a stud 45 projecting from the side wall 14 of the casing, shoulders provided upon said bolt adjacent to its head engaging the inner side of the front wall 11 of the casing (Fig. 1) to limit the movement of the bolt under the influence of the spring.

Slidably mounted in position within the casing 10 alongside the inner end of the bolt 37 is a bolt-pushing element or member 46 (Figs. 1, 2 and 13) made with a laterally extending stud 47 occupying a longitudinal slot 48 formed in said bolt. When the element or member 46 is slid toward the right (Fig. 1) the stud 47 thereof abuts the end of slot 48 and retracts the bolt and when member 46 is released the spring 44 returns the bolt and member to the positions shown in Fig. 1.

The pusher member 46 is normally locked at the limit of its movement toward stud 45 by a detent 49 and as will be clear the bolt is free to be retracted independently of member 46 either by the usual striker plate (not shown) when the door is closed, or by finger pressure on the stem or rod 39. Pusher member 46 is made with a cam shoulder 50 (Fig. 1) which normally occupies a position behind a cam shoulder 51 provided upon the under side of detent 49 which, in turn, is normally locked in this position by the tumblers 7, 5 and 3. When detent 49 is freed through adjustment of the tumblers as presently to be described, pusher member 46 may then be shoved in a direction to retract the bolt by pressure imposed upon the stud 47 by the arm 28 of rocker 17, as will be clear.

Pusher member 46 is made at its inner end with a slot 52 (Figs. 2 and 13) in order to permit the finger piece or stem 39 to be screwed into the threaded hole 40 from either side of the door and for the same reason the side wall 14 of the casing is made with a slot 41a which is identical with, and directly opposite, the slot 41. This readjustment of the finger piece or stem 39 will require that the slot 42 (Fig. 3) be made in the side wall of the mortise opposite to that in which it is shown. Sometimes the "outside" and "inside" of the door is the reverse of that shown in Fig. 3 in which case it becomes necessary to

shift the finger piece or stem as described so that it will be disposed upon the inside of the door. With the finger piece or stem arranged as shown in the drawings the slot 52 is not utilized, but 5 when the finger piece or stem is inserted from the opposite side of the door it will loosely occupy said slot 52.

The three tumblers 7, 5 and 3 are slidably mounted within a trough 53 forming a rigid part 10 of the casing, in positions to co-operate with the pawls 7a, 5a and 3a, respectively, and are slidably confined between the bottom wall of the trough and a top wall section 54 thereof. Longitudinal ribs provided upon the top side of the 15 bottom wall of the trough act as separators which prevent the tumblers rubbing against each other so that either can be adjusted endwise without disturbing the others.

The bottom wall of the trough 53 is cut away 20 to provide a passage or gate 55 for an upstanding wing or blade 56 provided upon the top side of detent 49 (Figs. 7 and 8) which is loosely pivoted upon a stud screw 57 projecting from the side wall 14 of the casing. Thus, the detent 49 25 normally rests by gravity upon the pusher member 46 with the top edge of blade 56 immediately below the bottom edges of the three tumblers 7, 5 and 3.

At 57' is a cross-bar forming a rigid part of the 30 trough structure 53 which assists top wall section 54 in holding the tumblers in position within the trough. This cross-bar 57' is spaced away from the adjacent end of top wall section 54 to provide a passage through which the pawls 7a, 5a and 3a 35 have access to the tumblers.

The master slide 38 is supported by the top 40 wall section 54 of trough 53 and is fitted into position between the opposite side walls of the latter by which it is guided in its movements. A flat leaf spring 58 fastened to one end of trough 53 bears at all times against the top of master slide 38 and frictionally holds the latter in position within the trough.

As shown in Fig. 9 the master slide 38 is made 45 with three laterally and longitudinally off-set gateways 59, 60 and 61, the gateway 59 permitting only pawl 7a to have access to its tumbler 7 when the master slide occupies position against a stop 62 as in Fig. 7; the gateway 60 permitting 50 only pawl 5a to have access to its tumbler 5 when the master slide is adjusted one step movement toward the left from the position shown in Fig. 7, and the gateway 61 permitting only pawl 3a to have access to its tumbler 3 when the 55 master slide is adjusted two step movements toward the left from the position shown in Fig. 7.

As shown in Figs. 10, 11 and 12 the three tumblers 7, 5 and 3 are all of the same size and shape except for the position of a notch 63 that is provided upon the bottom side of each, and 60 as shown each tumbler is provided upon its top with a rack of teeth, the teeth of all of the tumblers being aligned transversely when said tumblers occupy their normal positions against a stop wall 64 provided at the inner end of trough 53, as shown in Fig. 1.

When the tumblers occupy their normal positions against the stop wall 64 and master slide 38 is in engagement with its stop 62, the gateway 59 of the latter is in position to permit pawl 7a to act upon tumbler 7; the notch 63 of tumbler 7 is seven teeth distant from the gateway 55 of trough 53; the notch 63 of tumbler 5 is five teeth distant from said gateway 55, and 75 notch 63 of tumbler 3 is three teeth distant from

gateway 55. Now, by means of either knob 22 or 23 the rocker 17 (Fig. 1) is brought into the position shown where the abutment 26 of flange 24 is against the leaf spring 36 after which the rocker is turned in a clockwise direction to the limit of its movement in that direction. During this clockwise movement the cross-bar 30 (Fig. 1) acts through hook 31 and lever 32 to restore the master slide and all of the tumblers to their normal innermost positions. Rocker 17 is then turned contra-clockwise until shoulder 26 is brought into position against leaf spring 36 thus placing the parts in the positions shown in Fig. 1, with pawl 1a resting on top of tumbler 7. Rocker 17 is now rocked back and forth seven times starting with movement in a clockwise direction and each rocking movement being limited by the stop shoulders 25 and 26 of rocker flange 24. As will be clear, each clockwise rocking movement causes pawl 1a to shift tumbler 7 to the extent of one tooth so that at the conclusion of the seven reciprocating movements of the rocker the notch 63 of said tumbler 7 is in register with the gateway 55 of trough 53. Next, the rocker 17 is moved contra-clockwise to an extent limited by the engagement of its arm 28 with stud 47 which at this time is held immovable by detent 49, this movement of the rocker bringing the three pawls into position upon the top of spring 58 and into position behind a transverse abutment rib 65 as shown in Fig. 7. The rocker is then turned in a clockwise direction to an extent determined by the engagement of shoulder 25 with leaf spring 36. Just before the completion of this movement the tails of all of the pawls engage the hub of the rocker as shown in Fig. 8 so that as the movement is completed the pawls are lifted out of engagement with the master slide 38. During the movement of the rocker from the position shown in Fig. 7 to the position shown in Fig. 8 the free ends of the pawls engage the abutment rib 65 of the master slide and shift the latter outwardly sufficiently to move the gateway 60 thereof (Fig. 9) into operative position between pawl 5a and tumbler 5 and gateway 58 out of its operative position between pawl 1a and tumbler 7.

After adjustment of the master slide 38 into the position shown in Fig. 8 the rocker 17 is rotatively reciprocated five times thus causing the pawl 5a to adjust tumbler 5 outwardly into a position where its notch 63 registers with the gateway 55 of trough 53 and is alongside of the notch 63 of tumbler 7. As before, the last contra-clockwise movement of the rocker is extended beyond the engagement of shoulder 26 with leaf spring 36 to bring all of the pawls into positions upon the top of spring 58 and arm 28 against stud 47. The rocker is then turned clockwise to an extent determined by the engagement of shoulder 25 with leaf spring 36 and during this movement the noses of the pawls slide off from spring 58 into position behind a second transverse abutment rib 67 provided upon the top side of the master slide 38 through which said pawls act to adjust the latter outwardly so as to bring the gateway 61 of said slide into cooperative relationship with pawl 3a and tumbler 3. This last movement of the rocker is terminated when the shoulder 25 engages the leaf spring 36.

The rocker is now rotatively reciprocated back and forth from this position three times, starting with a contra-clockwise movement thereof and stopping with the shoulder 25 against leaf

spring 36. This imparts three step movements to the tumbler 3 at the conclusion of which the notch 63 thereof (Fig. 12) is opposite gateway 55 and aligned alongside the notches 63 of tumblers 7 and 5.

In this way the detent 49 is freed from the control of the tumblers so that if the rocker 17 be now swung or turned contra-clockwise to the limit of its movement in that direction, the arm 10 28 will act through the stud 47 to slide the pusher 46 (Fig. 8) toward the right thus causing said stud to retract the bolt 31 against the pressure of spring 44 until a shoulder 68 on the pusher member engages a shoulder 69 on the casing. 15 During this movement of the pusher member its cam surface 50 acts against the cam surface 51 to swing detent 49 aside and the latter rides upwardly on to the top of said member, the wing or blade 56 of the detent being at this time free 20 to rise into the notches 63 of the tumblers.

Upon release of the rocker 17 the spring 44 returns bolt 31 and pusher member 46 to their normal positions with cam 51 of the detent behind the cam 50 of the pusher member and with rocker 25 arm 28 in the position indicated by broken lines in Fig. 7.

By rotatively adjusting the rocker clockwise from the position indicated in Fig. 7 to the limit of its movement in that direction, the lever 32 (Fig. 1) may be operated to re-set the tumblers 30 as above mentioned, so that if and when the door occupies its closed position it can be opened only by utilizing the combination 7—5—3 as above described or by means of the finger-piece 39 (Figs. 1, 2 and 3).

While the rocker is being rotatively reciprocated to adjust each tumbler the nose of leaf spring 36 occupies a position between the two shoulders 25 and 26 and the resistance imposed 40 upon the rocker by spring 36 when either shoulder is brought into engagement therewith is a signal to the operator to reverse or stop the movement of the rocker.

From the above description it will be observed 45 that the master slide 38 serves as a shield which prevents two of the three pawls from engaging their tumblers while the other pawl is in action and that through the step-by-step adjustment 50 of the master slide as above described the pawls are successively thrown into action. It will also be clear that the order in which the pawls are thrown into action is immaterial so long as the combination is made appropriate.

When the three pawls are utilized simultaneously to adjust the master slide as above described and are slid forwardly off from the spring 58 (Figs. 7 and 8), that pawl 5 or 3 that is being brought into action falls on to a small shelf 70 (Fig. 9) so that all of the pawls are held out of 60 engagement with their tumblers until the first step adjustment of the master slide is completed.

The outside diameter of the split friction clutch bushing 19 (Fig. 6) is slightly greater than the internal diameter of the barrel or hub of the rocker so that it is slightly contracted when 65 installed within the rocker and provides a strong frictional connection between spindle 21 and the rocker. The purpose of this is to prevent injury to the lock mechanism through the application of 70 great force to the outer end of the spindle as by means of a wrench.

Herein gravity is depended upon to yieldingly urge the members 31, 49, 1a, 5a and 3a toward their normal positions but it will be clear that 75 this may be supplemented by springs if desired,

and when such be the case the lock may be mounted within the mortise in a position upside-down from that shown, if desired. This reversal of the lock may be resorted to when necessary to render the bevel upon the outer end of the bolt appropriate to the door to which the lock is applied, but will not be necessary when the outer end of the bolt is not beveled as shown.

While the rocker member is being rotatively reciprocated to cause one of the pawls to adjust its tumbler, and while the rocker member is being turned clockwise, the nose of the pawl is in engagement with one of the teeth of its tumbler and the latter is moved with the pawl until the tail 66 of the latter engages the barrel or hub of the rocker whereupon the nose of the pawl is lifted out of engagement with the tumbler. In this way the pawl acts to move its tumbler one tooth for each reciprocation of the rocker. It will be understood also, that each tumbler adjusting reciprocation of the rocker is made within the limits determined by the engagement of the abutment shoulders 25 and 26 with leaf spring 36; that when operating lever 32 to re-set the tumblers and master slide 38 the shoulder 25 is forced clockwise past the spring 36; that when operating the rocker to place the pawls in position to adjust the master slide as shown in Fig. 7 the shoulder 26 is forced contra-clockwise past the spring 36 to bring the arm 28 against the stud 47 of pusher 46 which is then locked against displacement by said arm, and that when operating the rocker to cause arm 28 to retract the bolt the contra-clockwise movement of arm 28 is continued beyond the position thereof indicated in Fig. 7.

What I claim is:

1. A door lock of the character described having, in combination, a movably supported bolt; a movably supported bolt-retracting member; an adjustable detent for normally holding said bolt retracting member against movement in a direction to retract said bolt; a set of movably supported tumblers for controlling said detent and normally securing the same in its operative position, each of said tumblers being made with a rack of teeth; a bolt-operating spindle; a plurality of pivoted pawls carried by said spindle, one for each tumbler; an apertured tumbler-shielding master member adjustably supported in position to control the engagement of said pawls with the racks of said tumblers, said member being adjusted by said pawls to cause the latter to successively engage and successively adjust said tumblers when said spindle is rotatively reciprocated in a predetermined manner thereby to free said detent and said bolt-retracting member; means through which said spindle acts, when reciprocated in said predetermined manner, to operate said bolt-retracting member to retract said bolt after it has been freed, and

means through which said spindle acts, when reciprocated in said predetermined manner, to restore said tumblers and said master member to their normal positions after said bolt retracting member and bolt have been operated.

2. In a door lock of the character described, the combination with the slidably supported spring pressed latch bolt, of a slidably supported pusher member disposed alongside of said bolt and made with a laterally extending stud projecting through a longitudinal slot formed in said bolt and engageable with one end of said slot to retract said bolt when the pusher member is slid in one direction; an adjustable detent normally holding said pusher member against bolt-retracting movement; adjustable tumblers for securing said detent in its normal position; a rotatably supported manually operated spindle; means through which said spindle acts to adjust said tumblers to free said detent when said spindle is rotatively reciprocated in a predetermined manner, and an arm carried by said spindle for engaging said stud thereby to impart a bolt-retracting movement to said pusher member after said detent has been freed.

3. In a lock of the character described the combination of claim 2 and wherein said spindle is provided with a handle that is disposed upon the outside of the door upon which the lock is mounted and wherein said bolt is provided with a laterally extending finger-piece accessible from the inside of the door by means of which the bolt may be retracted independently.

4. A door lock of the character described having, in combination, a movably supported bolt; a movably supported bolt-retracting member; an adjustable detent or keeper normally holding said bolt-retracting member against movement in a direction to retract said bolt; a set of movably supported tumblers controlling said detent or keeper and normally securing the same in its operative position; a spindle that is manually reciprocated rotatively, and mechanism through which said spindle acts when rotatively reciprocated in a predetermined manner to first successively adjust said tumblers to free said detent or keeper and said bolt-retracting member and thereafter operate said member to retract said bolt, each of said tumblers being formed with a rack of teeth, and said mechanism including a plurality of pawls carried by said spindle, one for each tumbler, and an apertured tumbler-shielding master member adjustably supported in position to control the engagement of said pawls with the teeth of said tumblers and which is adjusted by said pawls to throw the latter into action successively when the spindle is reciprocated in said predetermined manner.

WILSON S. SIDELINKER.
